PAUL L. MARDIS, OF WILKINSBURG, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,355,490.

Specification of Letters Patent. Patented Oct. 12, 1920.

Application filed February 13, 1917. Serial No. 148,431.

To all whom it may concern:

Be it known that I, PAUL L. MARDIS, a citizen of the United States, and a resident of Wilkinsburg, in the county of Allegheny and State of Pennsylvania, have invented a new and useful Improvement in Systems of Control, of which the following is a specification.

My invention relates to systems of control 10 and particularly to systems of control for electric railway vehicles.

One object of my invention is to provide a control system of the above indicated character which shall energize and operate 15 various signaling means and electrically operated switches in a safe and economical manner.

Another object of my invention is to provide a control system of the above indicated 20 character with a line switch for connecting a motor across the supply circuit, which shall be provided with an energizing coil that is connected in shunt to a portion of a plurality of resistors which are connected 25 across the supply circuit, and means comprising a controller and a plurality of interlock switches associated with the vehicle doors for selectively controlling the energization of said line-switch coil.

Another object of my invention is to provide a control system of the above indicated character which shall be provided with a trip switch that is disposed in circuit with the coil of the line switch and is provided 35 with an energizing coil which is disposed in series with the propelling motor of the vehicle, and a holding coil which is adapted to be energized in shunt to a portion of a plurality of resistors.

A further object of my invention is to provide a control system for an electric railway vehicle which shall have a line switch that connects a motor across the supply circuit and is associated with an auxiliary interlock switch to effect reduction of the voltage supplied to the line-switch coil when the latter is energized, and means for operating signal lights and for preventing the operation of the vehicle when one of 45 the vehicle doors is open.

In the prior art, systems of the above indicated character are disclosed in which the

various interlock switches are adapted to break the full line voltage when opened, and the coils of the various switches and signal 55 lights are connected in series with resistors across the supply circuit.

According to my invention, the coils of the various switches that serve to control the operation of the system are energized in 60 shunt to a portion of a plurality of resistors which are connected across the supply circuit, and the various interlock switches, which are operated by the doors of the vehicle, serve to break currents at reduced 65 voltages.

Figure 1 of the accompanying drawing is a diagrammatic view of a control system constructed in accordance with my invention, Fig. 2 is a diagrammatic view illustrating the relation of the door-interlock switches which are associated with one of the vehicle doors, Fig. 3 is a diagrammatic view of the line switch, and Fig. 4 is a simplified perspective view of a slip-segment 75 employed in connection with my invention.

Referring to Fig. 1 of the accompanying drawing, two motors M1 and M2 are connected across a supply circuit, comprising a trolley conductor 1 and a ground return conductor g, by means of a line switch LS, and are accelerated by means of a controller MC which excludes a resistor 2 from the circuit of the motors in a step-by-step manner. The controller MC embodies a movable contact segment 3 which is adapted to engage the contact fingers 4 to 7, inclusive, when moved through positions a, b and c, and an interlock switch 8, for completing a circuit through the coil of the line switch when the controller is in position a. The controller is further provided with a slip segment 9 shown in Fig. 4, of the type disclosed in the application of N. W. Storer, Serial No. 774,394, filed June 18, 1913, patented Sept. 11, 1917 No. 1,239,840, and assigned to the Westinghouse Electric & Manufacturing Company. The slip segment 9 serves to connect a plurality of resistors 10, 11 and 12 across the supply conductors 1 and g when the master controller is moved in a forward direction and to break the circuit of the resistors when the master controller is moved in a reverse direction a predetermined dis-

tance. As the operation of the slip segment is well-known in the art and is fully described in the application above referred to, it is deemed unnecessary to describe the 5 same in detail.

The line switch LS is provided with a coil 13 which is adapted to be connected in shunt to the resistor 12 by means of the drum interlock switch 8 and two door interlock 10 switches 14 and 15, when an overload trip switch OT is in the released position. The line switch is provided with two interlock switches LS-out and LS-in which are respectively adapted to close circuits when the 15 line switch is in the deenergized and in the energized position. The interlock switch LS-out serves to short-circuit the resistor 11 when the line switch LS is released, and the interlock switch LS-in serves to complete a holding circuit through the coil 13 when the controller is moved to position *b* or position *c*, and the interlock switch 8 is opened.

The overload-trip switch OT is adapted 25 to bridge a pair of contact terminals 16, when in the released position, and to bridge a pair of contact terminals 17, when in the operative position. The overload-trip switch embodies an energizing coil 18 which 30 is inserted in series with the motors M1 and M2, and a holding coil 19 which is energized in shunt to the resistor 12, when the overload-trip switch is energized to bridge contact terminals 17.

35 A circuit, comprising a door-interlock switch 20, a signaling means 21 and a resistor 22, is connected across the supply circuit in shunt to the slip segment 9 and to the resistors 10 and 11.

40 Assuming the doors of the vehicle to be closed, the vehicle is operated by moving the controller to position *a* for completing a circuit from the supply conductor 1 through the slip segment 9, the resistors 10, 11 and 45 12 to the ground conductor *g*. The coil 13 of the line switch LS is energized by a circuit which may be traced from one terminal of the resistor 12 through the overload-trip switch OT, coil 13 and the interlock switches 50 15, 14 and 8 to the other terminal of the resistor 12. Thus, the line switch LS is operated to connect the motors M1 and M2 across the supply conductors 1 and *g*. As set forth above, the interlock switch LS-out is ar- 55 ranged for short-circuiting the resistor 11, when the line switch LS is open, to increase the current flowing through the resistor 12 and the voltage applied across the terminals of the coil 13. Thus, the closing of the line 60 switch LS is insured when the voltage of the supply circuit is low, and, when the line switch is operated, the short circuit around the resistor 11 is broken to reduce the voltage supplied to the terminals of the coil 13.

65 When the controller is moved through po-

sitions *b* and *c*, the various portions of the resistor 2 are successively excluded from circuit to accelerate the motors. When the controller is moved to position *b*, the interlock switch 8 is opened but the circuit of the coil 70 13 is not broken by reason of the closing of the interlock switch LS-in.

In case a door of the vehicle is opened when the controller is in an operating position, the circuit of the coil 13 of the line 75 switch will be broken, by means of one of the interlock switches 14 and 15, and thus release the line switch LS to break the circuit of the motors M1 and M2. In this regard, attention is directed to the fact that the motors cannot again be energized until the master controller is moved to the first operating position and a circuit completed through the coil of the line switch by means of the drum interlock switch 8. The opening of a vehicle door completes a circuit through the indicating lamp 21 so as to notify the operator of the vehicle that a door is open, whether the controller MC is in the "off" or in an operating position. When 90 the controller is in the "off" position and a door is opened, the lamp 21 is connected in series with the resistor 12 across the supply circuit by means of the interlock switch 20. In case a door of the vehicle is opened when 95 the controller is in an operating position, the lamp 21 is energized in shunt to the resistors 10 and 11.

When the vehicle is at rest, the controller MC may be moved to position *a*, so that the 100 vehicle will be started in motion whenever the doors thereof are closed.

In case the controller is in position *b* or *c*, and the motors utilize an excessive current, the coil 18 of the overload-trip switch 105 OT will be energized to operate the switch OT and break the circuit of the coil 13 of the line switch LS. When the line switch LS is released, the holding circuit of the coil 13 is broken by means of the interlock switch 110 LS-in. In case the controller is in position *a* and the motors utilize an excessive current, the overload-trip switch will be operated to break the circuit of the coil 13, but the interlock switch 8 is now closed, and, 115 unless the overload-trip switch is held in an operative position, the line switch LS will again be operated upon the bridging of the contact terminals 16 by means of the over- load-trip switch OT. In order to prevent 120 the intermittent energization of the coil 13 of the line switch, when the controller MC is in the initial position, the holding coil 19 of the switch OT is energized in shunt to the resistor 12 by a circuit including the 125 contact terminals 17 which are bridged by the overload-trip switch OT.

Modifications in the system and arrangement and location of parts may be made within the spirit and scope of my invention 130

and such modifications are intended to be covered by the appended claims.

I claim as my invention:

1. In a system of control for an electric vehicle, the combination with a supply circuit and a plurality of resistors connected across the supply circuit, of an indicating means, a switch for connecting the indicating means in series with certain of said resistors when a vehicle door is opened, and a line switch having a coil energized in shunt to a portion of said resistors. 5
2. In a system of control for an electric vehicle, the combination with a supply circuit, a plurality of resistors connected across the supply circuit, an electric motor, and a line switch for connecting the motor across the supply circuit, said line switch having an operating coil connected in shunt to a portion of said resistors, of means for automatically releasing the line switch to de-energize the motor in case a door of the vehicle is opened or an excessive current is utilized by the motor. 15
3. In a system of control for an electric vehicle, the combination with a supply circuit and a plurality of resistors connected across the supply circuit, of an electric motor, a line switch for connecting said motor across the supply circuit, said line switch having an operating coil energized in shunt to a portion of said resistors, and an interlock switch controlled by said line switch for short-circuiting a portion of said resistors when the line switch is deenergized. 25
4. In a system of control for an electric vehicle, the combination with a supply circuit and a plurality of resistors connected across the supply circuit, of an electric switch having an operating coil, means for connecting said coil in shunt to a portion of said resistors, and means for reducing the voltage supplied to the coil of said switch when the switch is operated. 40
5. In a system of control for an electric vehicle, the combination with a supply circuit, a plurality of resistors connected across the supply circuit, a line switch, a circuit in shunt to a portion of said resistors and comprising a coil of said line switch and a trip switch, and a motor adapted to be connected across the supply circuit by said line switch, of means comprising said trip switch for releasing the line switch to deenergize the motor in case an excess current be utilized by the motor. 50
6. In a system of control for an electric vehicle, the combination with a supply circuit, a plurality of resistors connected across the supply circuit, a motor, and a line switch for connecting said motor across the supply circuit, of a trip switch connected in series with the energizing coil of said line switch and in shunt to a portion of said resistors, and a holding coil for said trip 65
- switch, said holding coil being adapted to be energized in shunt to a portion of said resistors, under predetermined conditions. 70
7. In a system of control for an electric vehicle, the combination with a supply circuit and a plurality of resistors connected across the supply circuit, of a signal light, a line switch having an energizing coil, and door-interlock switches for severally connecting the signal light and said coil in shunt to portions of said resistors. 75
8. In a system of control for an electric vehicle, the combination with a supply circuit, a plurality of resistors connected across the supply circuit, a motor, a line switch for connecting the motor across the supply circuit, and a controller for governing the operation of the motor, of a plurality of door-interlock switches for connecting the coil of said line switch in shunt to a portion of said resistors when the controller is in its first position. 80
9. In a system of control for an electric vehicle, the combination with a supply circuit and a plurality of resistors connected across the supply circuit, of a motor, a switch for connecting the motor across the supply circuit, and interlock switches for connecting the coil of said switch in shunt to a portion of said resistors. 85
10. In a system of control for an electric vehicle, the combination with a supply circuit and a plurality of resistors connected across the supply circuit, of a motor, a line switch for connecting the motor across the supply circuit, interlock switches for selectively connecting the coil of said line switch in shunt to a portion of said resistors, and a trip switch in circuit with the coil of said line switch, said trip switch having an energizing coil in series with the motor and a holding coil adapted to be connected in shunt to a portion of said resistors. 95
11. In a system of control for an electric vehicle, the combination with a supply circuit, a plurality of resistors connected across the supply circuit, a motor, a line switch for connecting the motor across the supply circuit, a signal light, and means for connecting the signal light in series with, and in shunt to, portions of said resistors when a door of the vehicle is opened, of means governed by a controller and the doors of the vehicle for connecting a coil of said line switch in shunt to a portion of said resistors, a trip switch in series with the coil of the line switch and having a holding coil adapted to be connected in shunt to a portion of said resistors when the trip switch is operated, and an interlock switch associated with the line switch for short-circuiting a portion of said resistors when the line switch is deenergized. 110
12. In a system of control for an electric vehicle, the combination with a plurality of 125

of translating devices, of indicating means, and means responsive to the vehicle-door opening movement for connecting said indicating means in circuit with said translating devices.

13. In a system of control for an electric vehicle, the combination with a plurality of translating devices, of indicating means, means responsive to vehicle-door movement 10 for connecting said indicating means in circuit with said translating devices, and a motor-controlling switching device having actuating means energized from said translating devices.
14. In a system of control for an electric vehicle, the combination with a plurality of resistors and an electric motor, of a motor-controlling switch having an actuating coil

energized from said resistors, and means for automatically releasing said switch in response to a predetermined movement of a vehicle door. 20

15. In a system of control for an electric vehicle, the combination with a plurality of resistors and an electric motor, of a motor-controlling switch having an actuating coil, a controller for governing the operation of the motor, and door-interlock switch means for connecting said coil in circuit with said resistors when the controller occupies a predetermined position. 25 30

In testimony whereof I have hereunto subscribed my name this 29th day of January, 1917.

PAUL L. MARDIS.
